C. T. APPLETON.
Bleaching Apparatus.

No. 12,709.

Patented Apr. 17, 1855.

UNITED STATES PATENT OFFICE.

CHARLES T. APPLETON, OF ROXBURY, MASSACHUSETTS.

BLEACHING APPARATUS.

Specification forming part of Letters Patent No. 12,709, dated April 17, 1855; Reissued May 22, 1855.

To all whom it may concern:

Be it known that I, CHARLES T. APPLETON, of Roxbury, in the county of Norfolk and State of Massachusetts, have invented 5 certain new and useful Improvements in the Art of Bleaching, of which the following is a full, clear, and exact description, reference being had to the annexed drawings, making part of this specification, in which—
10 Figure 1 is a plan of the apparatus employed, Fig. 2 a vertical section upon the line A, A, of Fig. 1.

The nature of my invention consists in exhausting the air from the vat which contains the goods while they are undergoing the various operations in the process of bleaching by which means I am enabled to perform these operations with great dispatch and with far less labor than has heretofore been required for the purpose.

To enable others skilled in the art to make use of my invention I will proceed to describe the manner in which I have carried it out.

25 B is the vat which receives the goods, a perforated strainer or false bottom C, preventing them from falling to the bottom of the vat. This vat is closed by a tight fitting cover E suitably secured by means of screws 30 or otherwise. a is an outlet pipe and cock from the bottom of this vessel.

D is a branched pipe having two cocks b and c, the one being in communication with a head of water, to be used in the 35 various washings which the goods are to receive, and the other bringing steam for heating and boiling purposes.

The vessel E communicates by means of the pipe d with another vessel F, which latter is also furnished with a tight fitting cover G.

H is an air pump for the purpose of exhausting the air from the vessel F with which it communicates by means of the 45 pipe f.

e is a cock through which any liquid which passes into or condenses within the vat F, may be drawn off.

I, K, L, are vessels for the purpose of 50 containing chlorin, water, and soda, the water being used to temper the strength of the other solutions as may be required. The pipes i, k and l, also furnished with cocks as seen in the drawings, establish a com-

munication between these vessels and the 55 vessel B.

m, is a cock in the pipe leading from the air pump H to the vessel F.

It is evident that the various vessels should be made of materials calculated to 60 resist the action of the various agents employed, those from which the atmosphere is to be exhausted being of a suitable strength to sustain the outward pressure of the atmosphere.

65 Operation: The goods being placed in the vat B, cold water is admitted through the pipe D, and cock c, in sufficient quantity to cover them. The air pump is then put in operation and the air is exhausted from the 70 vessel F. The cock n, is then opened and the air is exhausted from the vessel B, which causes the globules of air within the pores of the goods to expand and escape. The atmosphere is then admitted and the liquid is 75

forced by the pressure of the atmosphere into the pores of the goods, left vacant by the expansion of the air. The water is then heated and the goods are allowed to sleep. The goods are then thoroughly washed in 80

the following manner. The air is exhausted from the vessels F and B and the cock m being closed to prevent the admission of liquid to the air pump the cock c, is opened and water is permitted to flow through 85

the goods into the vessels F and B. The cocks e and a are then opened and the water is permitted to flow from the vessels F and B. This operation is repeated until the water runs from the goods perfectly clear. 90

This I have found to be a most rapid economical and efficacious method of washing, the exhausting of the atmosphere freeing the fibers and pores of the goods of the globules of air which they contain, and which 95

prevent the ready admission of the water. Alkali is then introduced and the receiver is again exhausted for the purpose as before of bringing the liquid into more immediate contact with the fibers of the goods. The 100

goods are then boiled in the alkali by a steam worm or otherwise which may be done at a temperature below 212 if the air be exhausted from the vessel. The alkali being run off and water introduced, the goods are 105 thoroughly washed as before. The chlorin solution is then admitted to the goods, and the air is again exhausted. The sour is

then run in, the chlorine being first drawn off. Lastly the goods are again washed as before until the water which comes from them is no longer acid. The process is thus completed without removing the goods from the vat, and a great amount of labor and time is saved, as well as the space required for the accommodation of the cumbersome washing machines now in use.

10 What I claim as my invention and desire to secure by Letters Patent, is—

The combination of an air-tight vat for receiving and containing the goods, an appa-

ratus for exhausting the air therefrom, and the necessary vessels for containing the liquids used in the process of bleaching, whereby the various steps may be performed in a much shorter space of time than has heretofore been required, and without removing the goods from the vat, substantially as herein set forth.

C. T. APPLETON.
